UNITED STATES PATENT OFFICE.

JOHN J. BREWIS, OF CHICAGO, ILLINOIS.

BRICK-MACHINE.

SPECIFICATION forming part of Letters Patent No. 395,871, dated January 8, 1889.

Application filed January 23, 1888. Serial No. 261,655. (No model.)

To all whom it may concern:

Be it known that I, JOHN J. BREWIS, a citizen of the United States of America, residing at Chicago, in the county of Cook and State of Illinois, have invented certain new and useful Improvements in Brick-Machines, of which the following is a specification, reference being had therein to the accompanying drawings.

My invention relates to improvements in brick-machines, and is designed as an improvement on the machine for which Letters Patent No. 324,453 were granted to me August 18, 1885.

The object of my present invention is to provide a mechanism which will press the clay first on one side and then on the other, to exclude the air from the clay and to prevent the formation of cracks or seams in the brick, and at the same time give the brick a smooth and glazed appearance.

A further object of my invention is to remove the brick from the lower plunger by means of the clay-hopper in such a manner as to preserve the uniform shape of the brick and prevent the loose clay from adhering to the same.

Other novel features will be fully described hereinafter, and pointed out in the claims.

Referring to the drawings, Figure 1 is a side view of my improved machine. Fig. 2 is also a side view, partly in section. Fig. 3 is a front view, partly in section. Fig. 4 is a top or plan view. Fig. 5 is a top or plan view of the table of the machine and the mold-filling boxes. Fig. 6 is a sectional end view of the mold-filling boxes and the table on which they work. Fig. 7 is a side view, partly in section, of a machine in which single toggles are used. Fig. 8 is a side view, also in section, showing the shelf removed.

A indicates the sides of the machine, which are made of cast-iron or other suitable material and joined together by means of cross bars or braces, so as to form a solid and substantial structure.

B is a shaft mounted in suitable bearings in the frame A of the machine, one end of which is provided with a band-pulley, C, for receiving motion from any suitable source of power, while the other end is provided with a pinion-wheel, D, which meshes with and imparts mo-

tion to the gear-wheel E on the shaft F, said shaft being also mounted in suitable bearings in the frame A of the machine. The shaft F is also provided with a pinion-wheel, G, which 55 meshes with the gear-wheel H.

The gear-wheel H is mounted on the shaft I, said shaft being also mounted in suitable bearings in the frame of the machine and provided with a crank, K, to which one end 60 of the pitman L is secured, the other end of said pitman being secured to the toggle-levers M, as will more fully appear.

The outer ends of the shafts I are provided with wrist-pins N, to which one end of the levers O are secured, the other ends of said levers being secured to the ends of a shaft or bar, P, which connects the toggles Q.

The lower ends of the toggle-levers M and Q are connected to the cross-head R, to which 70 the upper plungers, S, are secured, said cross-head being adapted to work in suitable guides in the sides of the machine.

The upper end of the toggle-levers M and Q are connected to the cross head or bar T, which 75 is adapted to work in slots in the sides of the machine, said bar T being connected at its outer ends with the upper ends of the rods or bars U, the lower end of said bars being secured to the cross-head V, on which the lower 80 plungers, W, are mounted.

It will be noticed that when the toggle-levers M and Q are being operated by the pitman L and levers O through the shaft I, pressure is exerted by the top plungers on the 85 top of the brick, and the lower cross-head, V, with the plunger W are drawn up by the rods U to press the lower side of the brick.

A' is a bar, one end of which is secured to the base of the machine, while the other end 90 of said bar projects forward under the cross-head V, and is secured to the screw-rod B', said screw-rod being passed up through the bracket C' and provided with a hand-wheel, D', by which the rod A' is raised or lowered, 95 which regulates the distance the lower cross-head is to drop, and in this manner the lower plungers can be adjusted at any point within the mold, and thus regulate the amount of clay deposited in the molds. The lower side 100 of the cross-head V is provided with a rubber block, E', which receives the force of the blow

when the cross-head V drops down on the adjusting-bar A'.

F' are friction-rollers secured to the joint of the toggle-levers M, said friction-rolls being adapted to rest upon and travel on the shelves or brackets G', provided with curved or uneven surfaces, over which the friction-rolls pass and by which the pressure can be exerted either on the top or bottom of the brick, or vice versa; or by making the shelf straight or level on top the pressure can be applied from the opposite sides at the same time.

The curve, as shown at II', Fig. 2, allows the upper plungers to enter the mold and then come to a period of rest, while the lower plunger moves up a certain distance to give the pressure from below. Then the upper plungers are moved down again by the inclinations on the shelves G', thus giving two distinct travels or pressures at different times on the brick, which allows the air to escape from the clay and moves the clay back and forth in the mold during the pressing process, so that the sides of the brick are made smooth and free from cracks. For example, I will designate the pivot of the upper toggle as H⁴ and the pivot of the lower toggle, as H⁵, so that if the upper part of the shelf G' is on an arc of a circle with H⁴ as a center H⁴ will remain stationary and H⁵ will be moved up. If this arc is changed to an arc from H⁵ as a center, H⁵ will remain stationary and H⁴ will be lowered, so that any change in the shape of these two arcs will produce a corresponding change in the movements of H⁴ and H⁵, and in this way an intermittent pressure is exerted on the brick. If the upper side of the shelf G' is level, H⁴ will be lowered the same distance that H⁵ is raised.

I' are friction-wheels firmly secured in brackets K' on the outside of the frame of the machine, against which the levers O impinge to raise the toggle-levers and the upper and lower plunger after the pressing operation has taken place. This is accomplished in the following manner: After the toggles have been drawn into a vertical line and the pressure applied to form the brick, the projections L' on the levers O come in contact with the friction-rollers I', while the shaft I, continuing its motion, depresses the rear ends and raises the front ends of the levers O, the friction-rollers I' acting as fulcrums for said levers until the plungers are raised and the bricks ejected from the molds by the upward movement of the lower plungers. As soon as the bricks are ejected from the molds and the clay-box moves over to push the bricks off of the lower plungers, the lower plunger recedes, so as to allow the clay to fill the molds, as will more fully hereinafter appear.

The downward movement of the lower plungers is accomplished by the rear inclined portion of the projections L', passing over the friction-rolls I', which allows the entire pressing mechanism to drop in the slots of the side

frames. The continued rotation of the shaft I now brings the rear ends of the levers O to their highest points, and in its rearward travel the toggles M and Q are brought together and the requisite pressure applied to the clay to form a perfect brick.

M' is the feed-box which supplies the clay to the molds from the clay-hopper M'', said box being arranged to slide on the table N'.

The feed-box M' is connected at its rear end to the bell-crank lever O' by the bars P', said bell-crank being secured to or made part of the shaft O'', which is pivoted in the sides or frame of the machine.

The bell-crank lever O' is provided with a stud, P'', which projects into the cam-groove R', formed on the inside of the spur-wheel H, said stud being provided with a friction-wheel, Q', on the end which enters the cam-groove and prevents the sides of said groove from wearing the end of the stud P''.

The cam-groove R' is so formed that the bell-crank lever will be operated to move the feed-box forward, to push the newly-formed brick from off the top of the lower plungers, and also to fill the mold-boxes with clay when the lower plungers have dropped down to their lowest position in the molds, after which the feed-box is drawn quickly back out of the way of the upper plungers, as is usual in this class of self-feeding reciprocating machines.

The table N' is made with inclined sides, as shown in Fig. 6, and the sides of the feed-box M' are provided with guide-strips S', the lower edges of which are beveled to fit the inclined surfaces of the table. The guide-strips S' are made adjustable in any suitable manner, so they can be moved down as the lower surfaces are worn away.

The object of making the table inclined is to allow the clay which has found its way out from under the feed-box to drop down out of the way, and thus prevent the wearing away of the bottom of the feed-box and the top of the table.

T' is a piece of wood or other suitable material secured to the front end of the feed-box, the front edge of the piece T' being arranged to be on a line with the rear walls of the molds when the feed-box is in its rearward position, as shown in Figs. 2, 5, 7, and 8. The office or function of this piece is to prevent an accumulation of the clay on the table in front of the feed-box, which would be plastered onto the end of the brick in the forward movement of the feed-box if the piece T' were not used. A further advantage of the piece T' is that when the bricks are ejected from the mold they come up directly in front of said piece, and almost, if not quite, in contact with it, so that when the feed-box is moved forward the bricks will be pushed off the lower plungers onto the front end of the table N' without being injured, as would be the case if the feed-box were allowed to get well under way in its forward movement before it came in contact with the newly-formed

bricks. This is an important feature of my invention, for the reason that the bricks come from the machine in a most perfect form, without having their edges bruised or mashed 5 and without having lumps of clay adhering to the same.

The upper edge of the piece T' is beveled, as shown, so that the upper plunger in its descent will push the feed-box back out of the 10 way in case there is any lost motion in the mechanism which operates the feed-box.

In Figs. 7 and 8 I have shown a single toggle for operating the plungers instead of two, as has been described. In Fig. 7 I have 15 shown the adjustable curved shelf for giving the two pressures on opposite sides of the brick, as has been indicated, while in Fig. 8 I have shown an adjustable stop, A'', secured to the cross-head R, which allows the upper 20 plunger to enter the mold-box a certain and predetermined distance, so as to give the necessary amount of pressure to the top of the brick until the stop A'' strikes the top of the table and arrests the further downward movement of the upper plunger. The lower plunger 25 is now raised by the straightening of the toggles, so as to exert pressure on the brick, and in this way first a top and then a bottom pressure is exerted on the brick.

30 What I claim, and desire to secure by Letters Patent, is—

1. In a brick-machine for compressing substances into form, a toggle-lever or series of toggle-levers connected at their upper ends 35 to a movable cross-head which in turn is secured or connected to a cross-head supporting the lower plungers, and mechanism, substantially as described, for operating said tog-

gle-levers, in combination with the shelves G', having irregular surfaces, whereby pressure 40 is exerted first on one and then on the other side of the brick, as set forth.

2. In a brick-machine of the character described, the toggle-levers provided with friction-wheels F', in combination with the 45 shelves or ways G', having an irregular or broken surface, as set forth, whereby the plungers are caused to exercise a variable pressure on the clay.

3. In a brick-machine of the character described, the pitman or lever O, for operating the toggles, in combination with the fixed or stationary friction-wheels I', operating as a 50 fulcrum for said levers, as set forth.

4. In a self-feeding brick-machine of the 55 character described, the table N', having inclined surfaces, as described, in combination with the feed-box M', having the adjustable sides S', as and for the purpose set forth.

5. The cross-head V, provided with the rubber cushion E', in combination with the lever A', rod B', and hand-wheel D', whereby the 60 lower plungers are adjusted in the molds, as set forth.

6. In a brick-machine of the character described, the adjustable stud or bolt A'', secured to the cross-head R, as described, whereby the downward movement of the upper plungers is arrested, as set forth.

In testimony whereof I affix my signature in 70 presence of two witnesses.

JOHN J. BREWIS.
